UNITED STATES PATENT OFFICE.

MEYER M. KANE, OF CHICAGO, ILLINOIS.

STEAM-PRESSING MACHINE.

1,203,880.

Specification of Letters Patent.

Patented Nov. 7, 1916.

Application filed December 27, 1915. Serial No. 68,888.

To all whom it may concern:

Be it known that I, MEYER M. KANE, a citizen of the United States, residing at Chicago, in the county of Cook and State 5 of Illinois, have invented certain new and useful Improvements in Steam-Pressing Machines; and I do hereby declare the following to be a full, clear, and exact description of the invention, such as will enable 10 others skilled in the art to which it appertains to make and use the same, reference being had to the accompanying drawings, and to the letters and figures of reference marked thereon, which form a part of this 15 specification.

This invention relates to new and useful improvements in steam pressing and ironing machines and consists of various details of construction, combinations and arrangements of parts which will be hereinafter 20 fully described, shown in the accompanying drawings and then specifically defined in the appended claims.

I illustrate my invention in the accompanying drawings, in which:—

Figure 1 is a top plan view of my improved steam pressing apparatus. Fig. 2 is a view in elevation of a part of the apparatus. Fig. 3 is an enlarged detail in 30 elevation of the machine. Fig. 4 is a sectional view taken on line 4—4 of Fig. 3. Fig. 5 is a bottom plan view of a perforated plate upon one of the steam boxes. Fig. 6 is a similar view of the plate upon another 35 steam box. Fig. 7 is a view looking at the interior of one of the steam boxes. Fig. 8 is a vertical sectional view through a steam box as on the line 8—8 of Fig. 7, with the cover in place. Fig. 9 is a top plan view 40 showing a steam or gas box and pipe connections therewith. Fig. 10 is a longitudinal sectional view through the bottom of the box shown in Fig. 9. Fig. 11 is an enlarged detail in section of the parts in 45 elevation and the means for adjusting the support for the steam box. Fig. 12 is an enlarged detail in elevation of the support for regulating the irons. Fig. 13 is an enlarged detail view showing the yielding tele- 50 scoping pipe connections supporting one of the arms. Fig. 14 is a detail sectional view of one of the adjustable iron carrying members.

Reference now being had to the details 55 of the drawings by numeral, 1 designate

the legs supporting the frame 2 upon which the yoke 3 is mounted and which latter and the frame support a removable table 4, said yoke having an extension table 5 held upon the ends of the yoke. The said frame supports a steam pressing box 6, a detail of which is shown in section in Fig. 10 of the drawings, and which has angled lugs 7 upon the bottom thereof movable in the grooves formed in the horizontally disposed bars 8, 60 shown in Fig. 4 of the drawings. Said steam box has a gas pipe 9 leading thereto and which pipe has a valve 10 therein and which communicates with a union 12 into which a supply of gas is introduced through 65 the medium of the pipe 14. A pipe 15 leads from the union 12 and has a valve 16 therein which regulates the flow of gas to the drum 17 and from which latter a pipe 18 leads to the burner 19, affording fuel for a burner 70 to produce steam within the tank 20, the latter being provided with an exit spigot 21 and a gage 22.

Steam pipes, designated by numerals 23 and 24, lead from the tank, the former being provided with a valve 25 and communicates with the steam pressing box 6, as shown clearly in Fig. 9 of the drawings, said pipe leading through an aperture 27 into the chamber 28, shown in Fig. 10 of 80 the drawings. In the pressing box is a plate 29 which is perforated, as shown in Fig. 5 of the drawings, and is provided with an asbestos covering 30 over which a canvas 31 is drawn. Said plate 29 is reversible, 85 being flat upon one side and curved upon the other, being flat for the purpose of pressing trousers, skirts, etc., and the curved portion upon the opposite side being adapted for convenient use for pressing vests and 90 conforming to the shape of the body. Said canvas covering and asbestos sheet are held securely upon the box by means of the strap 31^x through the ends of which a screw 32^x passes and upon which a thumb screw 100 is mounted, affording means for drawing the ends of the strap in clamping relation with the coverings for the box. Said pressing box 6 is mounted upon the springs 6' and 6^a, shown in Fig. 10 of the drawings, 105 and is adapted to yield under pressure.

Upon reference to Figs. 9 and 10 of the drawings, it will be noted that the end of the box has a threaded aperture for the reception of the screw 31^b which is fastened 110

to the shoulder pressing attachment 31^a, which has a semi-cylindrical surface and also a flat surface.

The second steam pressing box is designated by numeral 33 and which has a burner 34 in its upper portion, as shown in section in Fig. 8 of the drawings, and a reversible plate 35, shown in Fig. 6 and similar to the plate shown in Fig. 5, is disposed at an inclination and forms the bottom of a steam chamber 36 to which a steam pipe 37 leads from the tank 20. Said plate 35 is also flat upon one side and curved upon the other. The gas burner 38 is also mounted in the chamber 36 and serves as a means for heating the steam and the pressing box. Said steam box 33 has supports 39 which pass through bosses 40 in the rack bars 41, as shown in Fig. 3 of the drawings. Coiled springs 42 are mounted between each boss 40 and the washers 43 and at the upper ends of the supports 39 are the heads 44 of said supports. Said rack bars, which have teeth upon their lower edges, have longitudinal movements within the horizontal parts 45 of the yokes 34, said rack bars being moved to different adjusted positions through the medium of the mechanism shown clearly in Fig. 11 of the drawings, in which the gear wheels 46 mesh with the teeth upon the rack bars and a gear wheel 47 mounted upon the shaft 48 intermeshes with the teeth of the gear wheel 46, said shaft 48 having fixed thereto a hand wheel 49, affording means whereby the rack bars may be moved back and forth and with it the steam pressing box 33.

Pivotedly mounted upon the shaft 50 is a depressible plate 51 having two ball-shaped members 52 near its free end and which serve as handles to depress the plate to cause the box 33 to be moved toward the under box 6. Projecting from the lower surface of the depressible member 41 is a flange 53, slotted as at 54 and is adapted to receive a pin 55 carried by the angle lever 56 which is pivotally mounted upon the pin 57 upon the bracket member 58. One arm of said lever 56 has the tread member 59, affording means whereby, as the lever is tilted by foot power, the plate 51 may be moved downward and with it the steam box 33. A coiled spring 60 is fastened at one end to a lug 61 upon the angle lever and the other end to one end of the plate 51, serving to return the plate to its normal position after pressure is relieved from the tread member.

In order to protect the garments being pressed, guards, designated by numeral 62 and shown in Fig. 3 of the drawings, are held about the steam boxes by means of friction clamps. The under steam pressing box 6 may be moved back and forth upon the frame by first removing the table 4 which is positioned in the path thereof.

65 The means for supporting the irons and

regulating the same is shown in Figs. 12 and 13 of the drawings, and in which two irons, designated respectively by numerals 70 and 71, are illustrated, the former of which has a handle 73 to which a bail-shaped member 74 is pivoted, said member 74 being in turn connected to a flexible shaft 75 which telescopes within the tubing 76, shown in Fig. 13, and which tubing 76 has a tubular shell 77 telescoping within it. An adjusting screw 78 is mounted in a threaded boss 79 upon the tubing 76 and frictionally engages the tubular shell 77, while a tube 80 telescopes within the shell 77 and is held in different adjusted positions by means of the set screw 81. A coiled spring 82 is connected to a hook 83 secured to a filler 84 in the tube 80 and is connected to a cross pin 85 held in apertures in the shell 77. A wire 86 connects said pin with a pin 87 passing through the walls of the tubing 76. By this means, it will be noted that the flexible shaft and the telescoping tubular connections afford means for adjusting the parts and regulating the tension of the spring. The upper end of the tube 80 has a yoke 88, shown in Fig. 12 of the drawings, carrying in its opposite walls a pin 89 upon which a grooved pulley 90 is journaled, as shown in Fig. 14, said pulley being adapted to ride upon the rod 91, thus permitting the yoke 88 to travel back and forth upon the rod, its movement in opposite directions being limited by the resilient buffers 92 and 93. The rod 91 is bent at an angle as at 94 and is supported in the standard 95. A lazy tong, designated by numeral 96 and shown in Fig. 12, supports a tubular shell 97 and which telescopes within a shell 98 having a set screw 99 mounted in the walls thereof and adapted to hold said shell 97 in different adjusted positions. A flexible shaft 100 is connected to the shell 98 by means of pins 101 and said flexible shaft 100 is connected to the stirrup-shaped member 102 which is fastened to the handles 103 of the iron 71.

Referring to Fig. 1 of the drawings will be seen ironing boards, designated by numerals 105 and 106, while a smaller ironing board 107 is pivotally mounted upon a pin 108 carried by the bracket members 109. Said boards are held at right angles to each other and afford means whereby two people may be utilizing the irons while the third operator may actuate the steam pressing boxes.

In operation, the steam is conducted to the steam boxes through the pipes shown and the boxes are kept at a high temperature through the medium of the gas burners 125 to which gas is supplied through the pipes, thus superheating the steam and drying the garment while being pressed. The garment is placed over the canvas covering of the lower steam box and pressure is applied 130

through the pivotal spring-pressed plate, causing the upper steam box to press down upon the garment. The hot steam issuing through the perforated box plates will cause 5 the garment to be dampened and the high temperature incident to the boxes being heated by the burners will cause the garments to quickly dry.

By the provision of the hand wheel and 10 rack bars, the upper steam box may be shifted back and forth as may be desired and the under box may be shifted by removing the table, causing the box to be held in any desired position relative to the upper one. By 15 the provision of the regulating means supporting the irons, the latter may be raised and lowered for the convenience of the operator, it being understood that the pressman does not press the pants upon the press 20 board but rather flat upon the table but, in pressing coats and vests, they are placed upon the board. By the provision of the regulators suspended as shown from the rod, the work of the operator is reduced to 25 a minimum, the spring inside of the tubing serving automatically to lift the iron, assisting the operator in lifting a portion of the weight of the iron but affording the full weight of the iron when the tailor is using 30 the same in pressing the garment.

What I claim to be new is:—

1. A combination steam pressing machine and ironing apparatus comprising a frame, steam pressing boxes, one box positioned 35 above the other, adjustable rack bars, bosses thereon, supports upon the upper box mounted in said bosses, means for moving the rack bars to hold the upper press box in different positions, a pivotal plate having 40 projecting portions adapted to contact with said supports for the upper box, and an angle lever adapted to actuate said depressible plate.

2. A combination steam pressing machine 45 and ironing apparatus comprising a frame, steam pressing boxes, one box positioned above the other, adjustable rack bars, bosses

thereon, supports upon the upper box mounted in said bosses, means for moving the rack bars to hold the upper press box in 50 different positions, a pivotal plate having projecting portions adapted to contact with said supports for the upper box, a pivotally mounted angle lever with a tread upon one end, a pin carried by said lever and movable 55 in a slot in the shank portion of said plate, the latter being adapted to contact with the supports for the upper box.

3. A combination steam pressing machine and ironing apparatus comprising a frame, 60 steam pressing boxes, one box positioned above the other, adjustable rack-bars, bosses thereon, supports upon the upper box mounted in said bosses, means for moving the rack bars to hold the upper press box in 65 different positions, a pivotal plate having projecting portions adapted to contact with said supports for the upper box, a pivotally mounted angle lever with a tread upon one end, a pin carried by said lever and movable 70 in a slot in the shank portion of said plate, the latter being adapted to contact with the supports for the upper box, and a spring fastened at one end to one end of said plate and its other end to said lever. 75

4. A combination steam pressing machine and ironing apparatus comprising a frame, steam pressing boxes, means for adjusting the upper box to different positions, rack bars, bosses carried thereby and in which 80 said supports are mounted, gear mechanism for actuating said rack bars, a pivotal plate mounted upon the frame, a pivotal angle lever having a tread thereon, a pin carried by said lever, a slot in the plate in which 85 said pin works, and a spring connected at one end to the plate and the other end to the lever.

In testimony whereof I hereunto affix my signature in presence of two witnesses.

MEYER M. KANE.
